UNITED STATES PATENT OFFICE.

SIGNE ERICKSON, OF OMAHA, NEBRASKA.

UNDERGARMENT.

Application filed June 18, 1927. Serial No. 199,828.

The present invention relates to wearing apparel, and has particular reference to an undergarment which is especially designed for women.

5 An object of the present invention is to provide a unitary garment adapted to embrace all of the essential features of the separate and independent garments heretofore worn, and wherein the various parts or portions are peculiarly inter-related and connected to each other, so as to eliminate to a large extent overlapping portions or extra thicknesses particularly at those parts of the body where they are least desirable, and to 10 thus provide a relatively light, cool and simply constructed garment.

Another object of the invention is to incorporate in a unitary garment structure peculiar features for supporting the hose, and 15 wherein the strain is placed directly upon the shoulders, so that the body portion of the garment is relieved from such strain and also the strain is removed from the waist.

A further feature of the invention is to 20 provide in a unitary garment structure a body portion, which is in the nature of a princess slip having the desired fullness at the front between the bust and the waist, and which at the same time is provided with 25 a bust support, which is arranged independently of the gathered or loose portion, and which is embodied in the line of support between the hose straps and the shoulder straps.

30 With the foregoing and other objects in view, the invention will be more fully described hereinafter, and will be more particularly pointed out in the claims appended hereto.

35 In the drawings, wherein like symbols refer to like or corresponding parts throughout the several views,

Figure 1 is a front elevation of a unitary garment constructed according to the present invention, the dotted lines showing the application of the garment to the figure.

Figure 2 is a vertical section taken through the same from front to back, the figure being shown in dotted lines, and

40 Figure 3 is a rear elevation of the garment with a portion of the same adjusted to disclose the hose supporting and other features.

Referring to the drawing, 10 designates the body of the garment which is in the form 45 of a princess slip of the usual configuration and desired length and which is supported

upon the shoulders by a pair of shoulder straps 11, which are secured at one end to the front edge portion of the slip 10 in spaced relation, and which are looped upwardly to 50 pass over the shoulders of the wearer and carried downwardly and stitched or otherwise secured to the rear edge of the slip 10 for loosely suspending the same. The shoulder straps 11 are carried downwardly at the inner side of the slip 10 to the waist, and as shown to advantage in Figure 3, are disposed substantially in parallel relation and held apart not only by their stitching to the upper edge of the slip 10, but also by an inelastic rear waist section 12. The waist section 12 retains the lower ends of the straps 11 in proper position at the back of the wearer and affords a means of connection 55 between the straps 11 and lower elastic hose supporter straps 13, which extend downwardly substantially in alinement with the straps 11, and which carry hose clasps 14 at their lower ends adapted to be secured to the hose at the back of the wearer.

The slip 10 is provided within its upper end and at its front with a bust supporting band 15 of preferably inelastic material which extends across the front of the garment and is stitched or otherwise secured at 60 16 at opposite sides of the slip 10, and is of suitable configuration and length to support the bust. The upper end of the band 15 is supported by the front ends of the shoulder straps 11, while the lower end of the band 15 is held taut against the figure by front straps 17, which are secured in spaced relation to the lower edge portion of the band 15 and extend downwardly to the waist. The lower ends of the straps 17 are secured 65 in spaced apart relation by a front inelastic waist section 18, and the straps 17 are continued downwardly within the front of the garment below the waist section. The lower ends of the straps 17 are provided 70 with elastic hose supporting straps or sections 19 provided with hose clasps 20 upon their lower ends adapted to be adjusted to the hose at the front of the wearer.

The waist band is completed by the provision of lateral elastic sections 21, which connect the opposite ends of the front and rear inelastic waist sections 12 and 18, and which impart to the waist band the desired elastic movement. It is, of course, understood that 75 various adjusting and gathering devices 110 may be used where desired, such as at the

top of the slip 10, in the waist band, or the like.

The inelastic section 18 is stitched or otherwise secured to the waist portion of the slip 10 at the front thereof and the upper portion of the slip between its upper edge and the waist band is left in slack position, so as to provide a fullness at the front of the garment, while at the same time not interfering with the fitting of the bust supporting band 15. The back of the slip 10 is left free to hang directly from the upper edge of the slip as well as the sides of the slip, so that the only restriction in the free suspension of the slip from the upper portions of the shoulder straps 11 is the securing of the front of the slip to the waist band.

The garment is also provided in its lower part with a bifurcated section 22 of any approved configuration, but which is provided with front and rear panel sections 23 and 24. The front panel section 23 is stitched or otherwise secured to the inelastic front waist section 18 at the inner side of the slip 10 and at its opposite lateral edges is cut away so as to leave the hips below the waist band free. The rear panel section 24 is of similar configuration, and has its reduced upper end detachably or otherwise secured to the rear inelastic waist band section 12 by buttons 25 or the like.

It will be seen that there is thus combined in the single garment the various features heretofore obtained only by separate and independent garments and that the parts are so connected together that various thicknesses, folds and the like as well as the various extending means are eliminated.

The garment is designed to be cool and loose fitting and for this reason the front and rear panel sections 23 and 24 are tapered upwardly so that sufficient width of the same only is provided at and below the waist band for attachment of the bifurcated sections 22 to the waist band and in such position that the sections 22 are supported directly and wholly upon the shoulder straps 11.

All portions of the garment are, therefore, supported from the shoulder straps 11 and the waist band is utilized merely as a connection between several of the sections or parts and for holding the front of the slip 10 in loose or full position at the front of the garment.

I do not wish to be restricted to the size, form and proportions of the various parts, and obviously changes could be made in the construction herein described without departing from the spirit of the invention, it being only necessary that such changes fall within the scope of the appended claims.

What is claimed is:—

1. An undergarment comprising a slip, shoulder straps secured to the upper front and rear edges of the slip for supporting

the same from the shoulders and extending downwardly within the slip at the back thereof, a waist band attached to the lower ends of said straps at the rear of the garment, a bust supporting band secured in the front of the garment at the upper front portion thereof, front straps disposed between said bust supporting band and the front of the waist band, said slip being attached at its front portion to the waist band and hose supporting means extending downwardly from the waist band in line with said shoulder and front straps.

2. An undergarment comprising a slip, a pair of shoulder straps secured at their front ends to the upper edge of the slip and looped upwardly and backwardly for engagement over the shoulders of the wearer and stitched to the upper rear edge of the slip for supporting the same, said straps extending downwardly within the back of the garment, a waist band connected to the lower ends of the straps, a bust supporting band in the front of the garment supported from the upper edge thereof, front straps between the lower edge of the bust supporting band and the waist band, hose supporting means suspended from the waist band in line with said shoulder and front straps, said waist band having front and rear inelastic sections spacing the lower ends of the shoulder straps apart and the lower ends of the front straps apart and having elastic lateral sections, and a bifurcated section within the garment having upwardly tapered front and rear panels secured to the front and rear inelastic sections of the waist band.

3. An undergarment comprising a slip, a breast supporting band secured across the inner side at the front of the slip and extending downwardly from the upper edge thereof, a waist band secured at its front portion only to the front of the slip at the waist thereof for holding the upper part of the front of the slip in slack position, a pair of shoulder straps stitched at their front ends to the upper edge of said slip for supporting the same and said supporting band and having their rear portions stitched to the upper rear edge of the slip and extending downwardly and secured to the rear portion of the waist band, front straps between said supporting band and the waist band for maintaining the supporting band taut against the wearer, hose supporting means including elastic sections suspended from the waist band in line with said shoulder and front straps, and a bifurcated section having front and rear panels tapering upwardly in width to free the hips at the sides of the garment and secured to the front and rear portions of said waist band.

In testimony whereof, I have affixed my signature.

SIGNE ERICKSON.
